(57) **CLAIM**

The ornamental design for a pair of eyeglasses, as shown and described.

DESCRIPTION

FIG. 1 is a front view illustrating my design for a pair of eyeglasses;

FIG. 2 is a top plan view thereof;

FIG. 3 is a left side view thereof; the right side being a mirror image thereof;

FIG. 4 is a front perspective view thereof;

FIG. 5 is a rear view thereof; and,

FIG. 6 is a bottom view thereof.

1 Claim, 6 Drawing Sheets(56)
